Patented July 8, 1975

235,750

CAR FOR ELEVATED RAILWAY

Lawrence K. Edwards, 565 Arastradero Road,
Palo Alto, Calif. 94306

Filed Oct. 2, 1973, Ser. No. 402,840

Term of patent 14 years

Int. Cl. D12—03

U.S. Cl. D12—40

FIG. 1

FIG. 3

FIG. 2

FIG. 4

FIG. 5

FIG. 6

FIG. 1 is a side elevational view of a car for elevated railway showing my new design;

FIG. 2 is a front elevational view thereof;

FIG. 3 is a rear elevational view thereof;

FIG. 4 is a side elevational view thereof opposite to that shown in FIG. 1;

FIG. 5 is a top plan view thereof; and

FIG. 6 is a horizontal sectional view taken along the line 6—6 of FIG. 1 showing the interior thereof.

I claim:

The ornamental design for a car for elevated railway, substantially as shown.
